THERMOMETER

Samuel Burrows, Chicago, Ill., assignor to Neo Products Co., Chicago, Ill., a corporation of Illinois

Application May 28, 1952, Serial No. 19,933

Term of patent 3½ years

(Cl. D52—7)

To all whom it may concern:

Be it known that I, Samuel Burrows, a citizen of the United States, residing at Chicago, in the county of Cook and State of Illinois, have invented a new, original, and ornamental Design for a Thermometer, of which the following is a specification, reference being had to the accompanying drawing, forming part thereof.

Fig. 1 is a perspective view of a thermometer, showing my new design;

Fig. 2 is a top plan view thereof;

Fig. 3 is a rear view thereof; and

Fig. 4 is an end elevation.

The characteristic features of the design reside in the portion shown in solid lines.

I claim:

The ornamental design for a thermometer, substantially as shown and described.

SAMUEL BURROWS.
